CAN WASHING MACHINE

Application filed December 13, 1930. Serial No. 502,176.

The invention relates to can washing machines such as milk and ice cream can washing machines.

Heretofore it has been the usual practice to wash milk cans and their covers by subjecting the same to a series of sprays of washing fluid during the intermittent passage of the cans either on a horizontally disposed rotary carrier or on an intermittently moving straight line conveyor and the sprays alone are relied upon to cleanse the cans and covers. Owing to the fact that sometimes the material sticks to the can and that there are many crevices or parts of the cans and covers which cannot be directly subjected to the scouring action of the sprays the cans are frequently not entirely cleaned. Heretofore it has been proposed to immerse the cans in a soaking bath by hand and thereafter subject the cans to the action of a series of sprays but because of the length of time this operation takes and the cost of labor incident to it, this procedure has been superseded by the first described method. The object of the present invention is to overcome the difficulties incident to the prior procedure of hand soaking by providing a machine in which the cans are automatically immersed and carried through a soaking tank and thereafter further cleaned, rinsed and sterilized by the action of sprays. While it is common practice to immerse bottles in a soaking tank while moving on an endless conveyor as a part of the washing process, the problem of handling milk cans capable of holding from three to eleven and one-half gallons of fluid or ice cream cans holding from six to twenty quarts of fluid so as to immerse such cans in a washing tank is, because of the buoyancy of the cans, not a mere matter of forcing the cans into the solution as this would require so much power as to make the apparatus impractical and consequently the present invention has been devised to provide a can washing machine in which the cans are filled with the soaking solution from an outside source as they enter the tank so that their buoyancy is overcome as they enter the soaking tank and thus permit the soaking operation to take place without the use of excessive power for driving the

can carrier. Furthermore, according to the present invention as the cans leave the soaking tank they discharge the solution in which they have been soaked into a trough which has an outlet directed into the mouth of a can about to enter the solution so that this can is weighted down as it enters the soaking tank and thus easily immersed.

A further object of the invention is to provide a milk can washing machine in which the cans and covers are carried through a complete cycle upon an endless conveyor which is intermittently driven by a simple form of drive mechanism.

A further object of the invention is to provide a simple form of valve control for spraying devices controlled by the conveyor.

A further object of the invention is to provide a can washing machine of compact arrangement in which the cans and covers when used are carried through the soaking tank on the lower run of the conveyor and are subjected to the action of sprays while on the upper run of the conveyor.

The invention further consists in the several features hereinafter set forth and more particularly defined by the claims at the conclusion hereof.

In the drawings, Fig. 1 is a side elevation view of one side of the machine embodying the invention.

Fig. 2 is a vertical sectional view of the machine taken generally on the line 2—2 of Fig. 3, parts of the conveyor being shown in elevation;

Fig. 3 is a vertical sectional view taken on broken line 3—3 of Fig. 2;

Fig. 4 is an end view with parts broken away and parts shown in section taken generally on the line 4—4 of Fig. 2.

Fig. 5 is a side elevation view of the other side of the machine, with parts broken away.

Fig. 6 is a detail sectional view taken on the line 6—6, of Fig. 2;

Fig. 7 is a detail sectional view taken on the line 7—7 of Fig. 1;

Fig. 8 is a detail sectional view taken on the line 8—8 of Fig. 1;

Fig. 9 is a detail sectional view taken on the line 9—9 of Fig. 1.

Referring to the drawings, the numeral 10 designates an enclosing casing open at one end 11 for the placement or removal of the cans and covers on the conveyor working in the casing. The lower portion of this casing forms a soaking tank 12 and the upper level of the cleansing fluid is indicated by the line 13, said tank having the drain openings 14 and 15, the opening 14 determining the upper level of the washing solution.

The sides of this casing carry curved channel members 16 or parts formed into channel members and disposed adjacent the opposite ends of the casing, and joined together with a straight channel member 17 secured above the bottom of the casing and with a straight track member 18 adjacent the top of the casing to form a pair of oppositely disposed continuous tracks 19 in which the rollers 20 of an endless conveyor work, said rollers running in said channels, see Figs. 2 and 3. Adjacent rollers 20 are connected together by links 21 on opposite sides of said rollers with adjacent ends of the links operatively connected together by the pivot pins 22 of the rollers. Alternate links facing the inner side of the rollers have hanger brackets 24 secured thereto and to can and cover carrying receptacles 25, said receptacles with their brackets forming cross frame connections for the spaced sections of the conveyor formed by the rollers 20 and links 21 so that the whole assembly forms an endless conveyor provided with spaced can and cover carrying receptacles.

Each of the receptacles 25 when used for milk cans, includes a can carrying portion 26 substantially fully open at one end 27 in which the base of the can 28 is free to move and contracted at its sides 29 at its other end and provided with flanges or ledges 30 to engage the mouth of the can but having a centrally disposed opening 31. Each receptacle also has a cover carrying portion 32 formed by a partition 33 and slot 34 in one side of said receptacle extending inwardly from the end 27 and of a width to receive the cylindrical portion 35 of the cover while the top 36 of said cover fits between the partition 33 and the adjacent side of the receptacle as seen in Fig. 3.

Inasmuch as the receptacles 25 are open at their bottom or outer ends so that the cans and the covers may be readily introduced into their respective compartments or removed therefrom, means are provided at the lower run and the ends of the conveyor for retaining the cans and the covers in said receptacles. For this purpose a curved support or plate 37 extends from the entrance opening of the casing down to the bottom of the tank, a series of transversely disposed can supporting rollers 38 are arranged in spaced relation at the bottom and along a line generally parallel to the conveyor track

for a portion of the ascending run of the conveyor at the other end of the tank, a cover supporting strip 39 is disposed adjacent the roller run as shown in Figs. 2 and 3, and another curved support or plate 40 is mounted at this end of tank as shown in Fig. 2. Thus it will be noted that when the conveyor is moved, the receptacles 25 will carry the cans and covers first through the soaking tank and then out of the same and along the upper run of the conveyor.

A partition 41 extends across and is secured to the sides of the casing and cooperates with a front plate section 42 to form a temporary storage tank or channel 43, said partition being inclined downwardly from the rear toward the front of the casing and communicating at its forward end with a discharge outlet or spout 44 which is aligned with the opening 31 in the receptacle then in that position and hence with mouth of the can with the result that as the soaking solution from the can in the position A and which has passed through the tank discharges its washing fluid into the tank or channel 43 said fluid will flow out of said tank through the spout 44 and into the can in the receptacle in the position B and thus weight down this can as it is moved into the soaking solution by the conveyor, thus overcoming the resistance occasioned by the buoyancy of the can to its immersion into the solution in the soaking tank. During the time the can and its cover pass through the soaking tank, the solution therein, generally containing a caustic, has a chance to disintegrate or soak off such foreign matter as may have adhered to the inside or outside of the can to be treated or in the case of an ice cream can any adhering sticky particles.

When the can and its cover reach the position A, the cover is subjected to pressure sprays of washing fluid delivered by a pump hereinafter described, through a nozzle 45 which is arranged at the side of the tank facing the interior of the cover as shown in Fig. 8.

When the can reaches the position C it is subjected to the action of a series of pressure sprays of washing fluid from the nozzles 46, directed upwardly into the interior of the then inverted can and when the can and cover reach the position D, the interior of the can is subjected to the action of a pressure spray of hot water from the nozzle 47 and to the action of live steam from a nozzle 48 while the cover is subjected to the action of a spray of hot water and steam delivered through the nozzle 49, see Fig. 9.

As shown when the can and the cover have reached the position D, the exteriors of the cans and covers are subjected to the action of hot water sprays directed from spaced series of inclined nozzles 51 and the top of the can is also subjected to the action of a steam

nozzle 52 which acts to blow off water that might tend to collect on the recessed bottom of the can and thus prevent the operator from being splashed with such water when the cans 5 are in a discharging position.

The present embodiment of the invention is a small machine so that the interior hot water rinse, the sterile rinse and the top hot water rinse occur when the can is in the position D but it will be understood that in the case of a larger or longer machine having a conveyor with a greater number of receptacles active in its horizontal runs that the sterilizing rinse from the steam jets for cans 10 and covers as well as the steam blow off for the tops of the cans may occur when the can and cover have been advanced from the position D to a position nearer the discharge.

It will also be noted that flexible rubber 20 curtains 53 are provided adjacent the receptacles when in the position D to confine the sprays and that a similar curtain 54 is provided adjacent the mouth of the receptacle in this position to prevent the passage of spray 25 into the space 55, see Fig. 2.

It will also be noted from Fig. 2 that a storage space or tank 56 is provided in the casing beneath the can in the position D so that the rinse water may be collected therein and carried out of the casing and be reused as hereinafter described.

A manifold 57 for heated drying air is provided with discharge outlets 58 to direct this heated air into the mouths or interior of the cans when in the positions E and F and likewise a drying air nozzle 59 provided with openings 59' and a similar nozzle 60 direct heated drying air against the interior of the covers when in said positions and some of 40 the air passing through the opening 31 of the receptacles also acts upon the outside of the cans and covers so that by the time the can and its cover reach the discharging position G they are thoroughly washed and dried and 45 ready to be removed by the operator who thereafter fills the then empty receptacle with another can and cover to be washed. It will also be understood that before the cans are placed in the machine they may be subjected 50 to the usual prerinse operation so as to lessen the frequency of change of the washing solution in the tank 12.

The means for driving the conveyor and for furnishing the washing fluids to the various nozzles will now be described.

Referring to Fig. 1, the numeral 61 designates a suitable electric motor whose shaft is connected by a pulley 62 and belt 63 to a pulley 64 on a shaft 65 having a worm 66 meshing with a worm wheel 67 fixed to a shaft 68 journalled in bearings 69 in the sides of the casing and cut off from the interior thereof by a sleeve 70. The shaft 68 has similar grooved cams 71 mounted thereon on opposite sides thereof and exterior to the casing

and a roller 72 carried in each instance by a lever 73 works in each of these cams. Each lever 73 is fixed on an oscillatory shaft 74 that extends through the casing and is isolated from the interior thereof by a sleeve 75 and each lever has a feed dog 76 pivotally mounted on a shaft 77 carried by the upper end of said lever and working through a slot 78 in the casing, see Figs. 1, 3 and 5. Each dog 76 has a curved roller engaging end portion 76' adapted to engage one of the rollers 20 and a spring pressed plunger 77' pressed outwardly by a spring 78' and associated with said end, said lever bearing an inclined rear face 79 cooperating with the plunger 77' to permit said lever to ride over the next roller on its return stroke. The cams 71 are designed to cause a forward feeding movement equal to the distance between centers of the receptacles to advance said receptacles from one position to another and with a dwell sufficient to allow the sprays to act efficiently on the cans and covers and then to cause a return of the levers to their position for forward feed. Inasmuch as the drive is not directly connected to the conveyor except through the dogs, means, shown in Fig. 5, are provided to prevent overrunning of the conveyor comprising a locking member 80 having a notch 81 engageable with a roller of the conveyor and secured to a lever 82 mounted on an oscillatory shaft 83 carrying a finger or lever 84 adapted to be engaged by a pin 85 on one of the cams 71 so as to release said member 80 from the conveyor during the forward feed of the conveyor by the levers 73 and dogs 76 and then lock said conveyor against movement during the return movement of said levers and dogs. It will be noted that a slot 80' is provided in the outer flange of the track 16 adjacent the members 80 and 82 to prevent interference. Thus it will be understood that the conveyor with the receptacles containing the cans and covers is given an intermittent step by step movement progressively around the tracks 19 in the casing and that this provides a relatively long period for the soaking treatment and dwell periods for the action of the previously described sprays.

The shaft 61' of the motor at one side is connected through a suitable coupling 86 to the shaft of a centrifugal pump 87 and at its other side through a coupling 88 to the shaft of a smaller centrifugal pump 89. The motor shaft is also connected by a pulley 90 and belt 91 to a pulley 92 on a shaft 93 connected by pulleys 94 and 95 and belt 96 to a shaft 97 for the impeller of a rotary type blower 98.

The inlet of the pump 87 connects by way of pipe 99 and strainer 100 communicating with the interior of tank 12, with the washing fluid in the soaking tank whereby some of this fluid is withdrawn by said pump and delivered under pressure to a discharge pipe 130

101 having a branch pipe 102 leading to the cover spraying nozzle 45 and a branch pipe 103 leading to the can spraying nozzles 46 and the pump preferably keeps up a continuous spraying of this washing fluid through said nozzles, the spent fluid draining back to the tank by way of the temporary storage tank 43.

10 In Fig. 1 there are a series of hand controlled valves; the valve 104 controlling the inlet of steam to a pipe 105, the valve 106 controlling the flow of steam to a pipe 107, the valve 108 controlling the flow of steam to a pipe 109, the valves 110, 111 and 112 being water valves controlling the flow of water respectively to the pipes 114, 113 and 115.

15 The pipes 105 and 114 communicate with a mixing device 116 whereby the cold water is mixed with and heated by the steam to a 20 temperature of for example one hundred and eighty degrees Fahrenheit and then passes into a hot water chamber 117 from whence it is conducted by a pipe 118 having a control valve 119 therein to branch pipes 25 120 and 121 leading to the fresh hot water rinse nozzles 49' and 47 for the covers and cans respectively.

30 Steam conducted through the pipe 107 is delivered to branch pipes 122 and radiator coils 123 and thence passes from the branch pipes 124 to a pipe 125 which leads into the washing solution in the tank 12 at about the point 126 and thus this waste steam serves to heat the washing liquid to the desired temperature. As the air delivered by the blower 98 passes upwardly through the heater 127 and between the coils 123 it is heated and is delivered through the outlet 128 to the manifold 57 and through the pipes 129 and 130 35 to the air drying nozzles 59 and 60.

40 Steam conducted through the pipe 109 is controlled in its passage therethrough by a valve 131 and proceeds by way of branch pipes 132 and 133 to steam jet nozzles 49 and 45 48 for the covers and cans respectively. A branch pipe 134 also leads off of the branch 132 to supply steam to the blow off nozzle 52.

45 The water pipe 113 is used to supply the rinse water tank 56 with its initial supply of water while the pipe 115 is likewise used to initially fill the soaking tank with its supply of water.

50 As previously noted the level of the washing fluid in the tank 12 is determined by the drain 14 and the level of the rinse water in the tank 56 is similarly determined by the overflow pipe connection 135.

55 Means are provided for controlling the opening and closing of the valves 119 and 131 for controlling the hot fresh water rinse and the steam jets respectively. These valves 119 and 131 are what are commonly known as whistle valves in which the valves are of the spring closed poppet type and opened 60 by a downward pressure on their stems. In

each instance a lever 136 having an adjustable screw tappet 137 is mounted on an oscillatory shaft 138 which is mounted to project into the casing and carries a lever 139 disposed in the casing at one side and provided with a roller 140 adapted to be engaged by a cam block 141 mounted on each receptacle and having inclined ends, said lever 139 being raised by said block 141 to depress the lever 136 to open both valves 119 and 131 when the cans and covers are in the dwell position D. Thus a certain amount of steam and hot water is conserved when the conveyor is in motion. It will of course be understood that where the machine is longer and the steam jet acts on the can after it has been advanced from the position D that the control for this valve would be varied to suit this condition. With the above construction it will be noted that the rims of the covers as they pass over the plates 37, 39 and 40 will turn and thus revolve the covers as they pass through the soaking tank since said covers are loosely mounted in the holders provided for them in the receptacles 25.

55 For removing the vapors that may tend to collect in the machine, a vapor outlet 142 is provided which in known manner is connected with a suitable exhausting device (not shown).

60 With a machine of the character or type above described not only can the containers such as milk cans and ice cream cans be more efficiently cleaned than with the usual straight line washer but the machine may be made more compact and occupy less floor space than such straight line washers and as it consists of fewer parts in the aggregate it may be more economically made than a straight line washer of equal capacity.

65 I desire it to be understood that this invention is not to be limited to any particular form or arrangement of parts except in so far as such limitations are specified in the claims.

70 What I claim as my invention is:

1. In a can washing machine, the combination of a tank adapted to contain washing fluid, a power driven conveyor for intermittently and progressively immersing and conveying cans through said tank, and means for weighting the cans with washing fluid to assist their immersion in the fluid in said tank.

75 2. In a can washing machine of the character described, the combination of a tank, means for intermittently and progressively immersing and conveying cans through a washing liquid in said tank and to a position above the same, and means for discharging washing liquid from a previously immersed can into a can about to be immersed to overcome the resistance occasioned by the buoyancy of the can to its immersion.

80 3. In a can washing machine of the character described, the combination of a casing

having a bottom portion forming a tank for washing fluid, means for intermittently and progressively immersing and conveying the cans through said tank and raising them from
5 the tank in an inclined discharging position, said casing provided with a temporary storage space for washing fluid discharged from the can after its immersion, and means for directing the washing fluid from said space
10 into the mouth of the can to be immersed to aid its immersion.

4. In a can washing machine, the combination of a casing having a tank formed in the bottom portion thereof adapted to contain
15 washing fluid, spaced tracks at the sides of said casing and forming a continuous trackway adjacent the top and bottom of said casing and around the ends thereof, an endless conveyor running on said trackway and including
20 receptacles, each having a can receiving portion open at both ends and having means adapted to support the cans in inverted position along the upper run of said conveyor and a cover receiving portion open
25 at one end, means cooperating with said receptacles to maintain the cans and covers therein while passing through said tank, and means for intermittently moving said conveyor, said casing having a feed and delivery
30 opening for loading and unloading of the receptacles at one point in the path of movement of said conveyor.

5. In a can washing machine, the combination of a casing having a tank formed in the lower portion thereof and adapted to contain a washing fluid, a vertically disposed endless conveyor disposed in said casing and including receptacles disposed in vertical position on the upper and lower runs of said conveyor
40 and movable into said washing fluid on its lower run and above the same on its upper run, each receptacle including a can receiving portion open at its ends and provided at its inner end with stops to engage the mouth of
45 the can when in inverted position and including a cover holding portion having a cover mouth receiving slot, and means for intermittently moving said conveyor.

6. In a can washing machine, the combination of a casing having a tank formed in the lower portion thereof and adapted to contain a washing fluid, a conveyor disposed in said casing and including receptacles for removably holding cans and covers, each receptacle
55 having a can receiving portion and cover receiving portion open at one end, means including spaced rollers in said tank for maintaining said cans in said receptacles as they pass through the tank, and means including
60 a track on which the rims of said covers ride and on which they are free to rotate as they pass through said tank.

In testimony whereof, I affix my signature.

JOSEPH HAUK.
